PROCESSING OF HYDROCARBONS

David L. Cramer, Long Beach, Calif., assignor to Texaco Development Corporation, New York, N. Y., a corporation of Delaware

No Drawing. Application March 30, 1951,
Serial No. 218,546

10 Claims. (Cl. 195—3)

This invention relates to the production of biosynthetics from hydrocarbons and more particularly to the production of fat-like saponifiable materials from hydrocarbons by the action of molds, yeasts, and other microorganisms, the invention being an improvement over the invention disclosed in the copending application of R. G. Harris and R. J. Strawinski filed August 17, 1950 bearing Serial No. 180,092 and entitled Processing of Hydrocarbons.

It has been known for some time that such microorganisms have the ability to attack or metabolize some materials such as carbohydrates. Since carbohydrates are relatively expensive raw materials and in most cases, of greater value than the products produced therefrom, other raw materials have been sought. A considerable amount of work has been done with hydrocarbons but to date it has not been generally successful and has not been on a practical basis, apparently because of the failure to appreciate certain factors as hereinafter described. Probably the most discouraging aspect of the hydrocarbon work done heretofore is the fact that the principal products have been carbon dioxide and water. Apparently, this has been due to a studied adherence to established methods of procedure and a failure to appreciate the possible effects of radical departures therefrom.

Accordingly, it is an object of this invention to provide novel processes wherein hydrocarbons can be effectively utilized in biosynthesis including the production of relatively high yields of fat-like saponifiable materials and other products.

Other objects and advantages of the invention will appear from the following description taken in connection with the attached claims.

In brief, it has been discovered that under certain conditions, microorganisms such as molds, yeasts and the like can be caused to grow quite rapidly upon relatively inexpensive substrates such as hydrocarbons in an emulsified phase with the production of relatively large yields of desirable products including fat-like saponifiable materials, and other products. Such conditions include such factors as the selection and maintenance of a proper pH range and temperature range, the selection of proper nutrient salts, and the selection of a proper emulsifying agent. In some cases, the selection of predetermined concentrations of both salts and substrates is desirable.

Broadly stated, the practice of the invention involves the use of a nutrient salt solution such as a solution of the mineral salts type with a pH in a selected range and the use of a hydrocarbon, the use of an emulsifying agent, preferably of a type capable of also functioning as a phosphorylating agent, the inoculation of the mixture with a selected microorganism or microorganisms, the maintenance of the mixture within predetermined temperature and pH ranges for a time sufficient to effect the desired biosynthesis, and the recovery of the desired products.

Any type of hydrocarbon can be utilized in the process. Good results can be obtained with complex hydrocarbons such as crude oil, kerosine, paraffin wax, naphtha, gasoline, gas oil, lubricating oils and bottom sediments from oil tanks. Of the above, even better results can be secured with certain selected cuts. For instance, a kerosine water white oil, sold by The Texas Company under the trade name "Crystalite" and having a B. P. range of 178° C.—261° C. can be fractionated into the following cuts:

2

	Cut	B. P. ° C.	Refraction Index	Specific Gravity
5	A	to 205	1.4388	0.8022
	B	205-215	1.4432	0.8118
	C	215-225	1.4454	0.8155
	D	225+	1.4500	0.8217
	Control or Charge	178-261	1.441	0.8118

10 Of the above cuts of kerosine, Cut D will usually give the best yield and product as expressed in grams of mold mycelia. Cut D will usually give a yield of over twice as much as Cut A, about 50% more than Cut B and about 33% more than Cut C.

15 Commercial stove oil, having a B. P. range of 167° C. to 277° C. can be similarly fractionated by ASTM distillation methods into the following four cuts:

	Cut	B. P. ° C.	Refraction Index	Specific Gravity
25	F	to 221	1.4541	0.8279
	G	221-235	1.4583	0.8351
	H	235-252	1.4631	0.8415
	I	252+	1.4681	0.8506
	Control or Charge	167-277	1.4590	0.8304

30 Of the above, Cut I will usually give a yield of about three times the yield of Cut F measured in mold mycelia, of about twice the yield of Cut G and about 1½ times the yield of Cut H.

35 Relatively simple hydrocarbons such as isopentane, n-pentane, 2,2-dimethylbutane, 2,2,4-trimethylheptane, n-heptane, isoheptanes, isoheptenes, isoctanes, isoctenes, 2,3-dimethylpentane, cyclopentane, butylbenzene, 2,2,5-trimethylhexane, 2,3-dimethylpentane, 2-pentane, methylcyclopentane, and 1-pentene can also be used as well as hexane.

40 Microorganisms suitable for use include molds, yeasts and the like. Typical examples are molds of the genus Penicillium such as *P. roqueforti*, *P. glaucum*, *P. chrysogenum*, *P. patulum*, and *notatum*, molds of the genus Aspergillus such as *A. fumigatus* (strain TDC #946), *A. carbonarius*, *A. niger*, *A. flavus* and *A. terreus*. Typical yeasts include *Monilia murmanica*, *Monilia sitophila* and *Saccharomyces*.

45 The majority of the above are available from the American Type Culture Collection. One such mold that is suitable for use is unidentified except for the number 50 9577.

55 One of the best microorganisms for use in the process of this invention is *Aspergillus fumigatus* (strain TDC No. 946) which has been identified as follows:

55 *Source of isolation*.—A mixed sample composed of soils taken from areas in which oils were undergoing decomposition and water taken from sumps, tank bottoms, and waters which had been in contact with refinery wastes; decomposing asphalt, wax and used motor oil were included in the sample.

60 *Date of isolation*.—October 1, 1947.

Location of isolation.—Signal Hill Laboratory, The Texas Company, Long Beach, California.

Media used for isolation.—A hydrocarbon-mineral salts medium composed of 5% Arabian crude oil (topped) and the following medium at pH 4.5.

	Compound	grams per liter	2.0
70	NaNO ₃	do	1.0
	KH ₂ PO ₄	do	0.5
	MgSO ₄ ·7H ₂ O	do	0.5
	KCl	do	0.5
	FeSO ₄ ·7H ₂ O	do	0.01
	Sea water	milliliters	10.0
	Distilled water	do	990.0

75 The above is generally designated Turfitt's Yeast and Mold Medium.

Conditions of isolation.—Aerobic, at 40° C.

80 Microscopic examination and a comparison of the essential morphological features with those of molds described in the literature indicate that the mold belongs to

the *fumigatus* group of the Aspergilli, the type species of which is *Aspergillus fumigatus*. A complete description thereof can be found in "A Manual of the Aspergilli" by Charles Thom, The William and Wilkins Company, Chapter X, pp. 148-151.

The character of the nutrient media or mineral salts solution will vary to some extent in accordance with the type of microorganism used and the type of hydrocarbon. Generally, it should contain N, P, K, S, Fe, Mg, the general composition being well known in the art. A typical medium is as follows:

Compound:

(NH ₄) ₂ SO ₄	grams/liter	2.0
K ₂ HPO ₄	do	2.0
NaH ₂ PO ₄	do	1.0
MgSO ₄	do	0.25
MnCl ₂	do	0.01
CaCl ₂	do	0.01
FeSO ₄	do	0.01
KI	do	0.00001
CuSO ₄	do	0.00001
Distilled water	milliliters	1000

In some cases, the medium may be fortified or enriched with accessory growth factors such as water extract of yeast such as *Saccharomyces cerevisiae*.

It is to be understood that the character of the medium may also be varied dependent upon the type of product that it is desired to produce in the most abundance.

As regards the mechanical or contact aspect, the process may be practiced in a number of different ways. In its simplest form, the growth may be accomplished in a static phase on the surface of the liquid mixture. Preferably it is practiced as a deep culture process by mechanical agitation such as stirring or shaking in the case of liquids. In the case of solid hydrocarbons, contact may be established and maintained by the method described in the copending application of Rhett G. Harris, Serial No. 12,896 filed March 3, 1948 and entitled Processes Involving Action of Microorganisms or Their Enzymes on Organic or Inorganic Substances wherein the hydrocarbon is adsorbed on a finely divided and relatively inert adsorbent material such as a clay. Where the hydrocarbon is in the gaseous phase, a system may be set up wherein the gas is recycled through the inoculated medium.

The pH with molds may vary from 1 to 9. With yeasts, the pH may vary from 4 to 9. Its selection is governed by the particular microorganisms, the particular hydrocarbon and the end products desired.

The same is true of temperature, the range being from 20° C. to 45° C. The actual time of incubation, usually from 7 to 12 days, is determined by the rate of growth of the microorganisms. This is governed by the ability of the enzymes produced by the microorganisms to effect production of the desired products.

The emulsifying agent may be one of the more common and well-known agents for emulsifying hydrocarbon and water but is preferably an agent which is preferentially soluble in the hydrocarbon but not in water. Thus, an emulsion is obtained in which water is the dispersed phase. This results in better contact of the microorganism which is essentially hydrophilic and the hydrophobic source of carbon. Stated otherwise, the resulting mixture is preferably one in which water or salt medium globules are dispersed in hydrocarbon.

It is further desirable that the emulsifying agent be characterized by apparent phosphorylating properties, i. e., capable of entering into the mechanism of fat re-synthesis in the animal body.

Calcium stearate is an example of one of the more common emulsifying agents that might be used but which do not possess phosphorylating properties. A preferred agent, capable of functioning in both an emulsifying and phosphorylating capacity, is lecithin which may be represented by the formula:

where R₁ and R₂ are fatty acid anions, such as oleate,

stearate, etc., and R₃ is the quaternary ammonium base choline.

Other monoaminomonophospholipids such as cephalin may be used as well as the diaminomonophospholipids of which the sphingomyelins are typical.

The proportion of emulsifier or phospholipid used in the process does not appear to be particularly critical. Amounts varying from 0.1% by volume of the hydrocarbon to as much as 10 grams per 100 ml. hydrocarbon have been found to produce satisfactory results. The amount of emulsifier used such as lecithin is so small that it would not be used by the microorganism as a carbon source.

As an example of a method embodying the present invention, lecithin is added to kerosine in a proportion of 0.1 gram of lecithin to 100 ml. of kerosine. The type of hydrocarbon used is not critical nor is the above-indicated proportion of lecithin critical. Proportions as high as 1 to 10 grams of lecithin to 100 ml. of kerosine have been found to be equally effective.

A suitable sterile mineral salts or nutrient solution is then prepared. Such a solution may vary widely in composition and proportion, the following being typical:

25	Distilled water	cc	900
	Sea water	cc	100
	K ₂ HPO ₄	g	2.0
	(NH ₄) ₂ SO ₄	g	2.0
30	MgSO ₄	g	0.25
	MnCl ₂	g	0.01
	CaCl ₂	g	0.01
	FeSO ₄	g	0.01
	ZnSO ₄	g	0.005
35	KI	g	0.001
	CuSO ₄	g	0.001

After sterilization, the pH of such a solution is about 5.5.

As already stated, the composition of the mineral salts solution may be widely varied provided that the following are supplied thereby:

Ammonium ion such as ammonium sulfate or nitrate
Magnesium ion
Phosphate ion

45 Iron and zinc ion (in traces)
Manganese, calcium, copper and iodide ions which appear to have a stimulatory effect
A suitable buffering system to absorb excess acidity that may result from the growth process. Good growths have been secured with an initial pH in the region of 4.5, 5.5 and 6.8.

50 A mineral salts solution, prepared as described above, is added to the kerosine-lecithin combination in a proportion of nine parts mineral salts solution to one part kerosine-lecithin.

The mixture is then stirred and an inoculum including the mycelial growth and the spores of a seed culture of a mold known to utilize the specific hydrocarbon as a source of carbon and energy, is added in an amount of from 0.1% to 20% by volume. The inoculum is formed as a thick suspension of the organism in the nutrient medium constituting about 10% by volume of the total charge. The amount of inoculum can be varied widely since such variation is limiting only upon the period of time subsequently necessary for growth of the mycelia to be fully established in the desired submerged culture.

While the method has been especially successful with *Aspergillus fumigatus* (strain TDC No. 946), the method is not restricted to this particular organism. Any strain of any species able to utilize the specific hydrocarbon as a source of carbon and energy may be used.

The culture vessel is then held at a substantially constant temperature in the range of about 20° C. to 45° C., preferably about 30° ± 3° C., and the mixture maintained in an agitated condition by shaking or stirring. Sterile air or oxygen, preferably at superatmospheric pressure, is introduced at a vigorous rate into the depths of the culture as through a porous bubbler.

After 5 to 10 days' operation under these conditions, the mold mycelia is harvested by mechanical separation such as filtration or centrifuging from the liquid portion of the culture.

As compared with the same method but with the

lecithin omitted, the yield of mold mycelia is increased from 200% to 300%.

To recover the fat-like saponifiable material, the mycelia can be dried and a crude extract prepared by chloroform extraction. After removal of the solvent, the residue is treated with approximately two-thirds its weight of potassium hydroxide dissolved in alcohol and refluxed to effect saponification. Following saponification about two-thirds of the solvent alcohol is removed by heating. The residual soap solution is then extracted with petroleum ether to remove the non-saponifiable fraction. Following this step, the aqueous liquor is made strongly acid with a mineral acid and the free organic acids extracted with diethyl ether.

The saponifiable material thus recovered does not consist exclusively of fatty acids of the usual aliphatic character. Some products are found which react chemically very nearly the same as the fatty acids but they are not the usual aliphatic fatty acids such as the straight-chain acids containing an even number of carbon atoms such as C_{10} acid (capric), C_{12} acid (lauric or dodecanoic), etc., such acids being usually obtained from the naturally-occurring fats.

The mixed fatty acids obtained are in the nature of pale yellow solids at room temperature with the characteristic appearance of a fat. A slightly, pleasant, fat-like odor is present and the taste is similar to that of candle tallow or similar stearins. The product melts at about 29.5°C . and has a setting point of 17.5°C . The mean molecular weight is 294, and the iodine number 83.5. Of the common fats or fatty oils, the product most closely resembled the mixed fatty acids from olive oil.

In another method, lecithin is added in an amount of 0.01% the volume of kerosine. About fifteen parts by volume of nutrient medium, prepared as above described, is added to two parts of the kerosine-lecithin mixture and the mixture inoculated with *Aspergillus fumigatus*. After seven days' incubation under agitation and aeration, a yield, dry weight of mycelia is obtained which is almost twice the yield of a control not containing lecithin.

If desired, the mycelia may be processed as described in the afore-mentioned Harris and Strawinski application to recover other products.

From the above it is believed apparent that the present invention provides a novel process for the synthesis of relatively valuable fat-like saponifiable materials and other products in relatively large yields from relatively cheap raw materials, i. e., hydrocarbons. The use of an emulsifying agent, particularly an agent possessing phosphorylating properties, is particularly advantageous in submerged, stirred and aerated culture processes.

Obviously many modifications and variations of the

invention, as hereinbefore set forth, may be made without departing from the spirit and scope thereof and, therefore, only such limitations should be imposed as are indicated in the appended claims.

5 I claim:

1. The method of synthesizing large yields of fat-like saponifiable materials from hydrocarbons which comprises the steps of dispersing hydrocarbon with a phospholipid in an aqueous nutrient medium for micro-organisms, inoculating the resultant mixture with a microorganism selected from the group consisting of *Penicillium* molds, *Aspergillus* molds, *Monilia* yeasts and *Saccharomyces* yeasts, subjecting the inoculated mixture to incubating conditions for a sustained period of time, collecting the resultant solid material and separating synthesized fat-like materials therefrom.
2. The method of claim 1 wherein said phospholipid is lecithin.
3. The method according to claim 1 in which said phospholipid is cephalin.
4. The method according to claim 1 in which said inoculated mixture is incubated at a temperature in the range of 20 to 45°C . and at a pH of about 1 to 9.
5. The method according to claim 1 in which said 25 microorganism is *Aspergillus fumigatus*.
6. The method according to claim 1 in which said microorganism is *Penicillium notatum*.
7. The method according to claim 1 in which said microorganism is *Aspergillus flavus*.
8. The method according to claim 1 in which said 30 microorganism is *Monilia murmanica*.
9. The method of increasing the yield of fat-like saponifiable materials obtained by the action of micro-organisms selected from the group consisting of the 35 *Penicillium* molds, the *Aspergillus* molds, the *Monilia* yeasts and the *Saccharomyces* yeasts on the hydrocarbon in aqueous nutrient medium which comprises the steps of adding a phospholipid emulsifying agent to the mixture of hydrocarbon and nutrient medium.
10. The method according to claim 9 in which said 40 phospholipid is lecithin.
